(57) **CLAIM**

The ornamental design for a speaker, as shown and described.

DESCRIPTION

FIG. 1 is a right, front perspective view of a speaker showing a first embodiment the new design in a first configuration; FIG. 2 is a left, rear perspective view of the invention illustrated in FIG. 1;

FIG. 3 is a front view of the invention illustrated in FIG. 1; FIG. 4 is a rear view of the invention illustrated in FIG. 1; FIG. 5 is a right side view of the invention illustrated in FIG. 1;

FIG. 6 is a left side view of the invention illustrated in FIG. 1;

FIG. 7 is a top view of the invention illustrated in FIG. 1; FIG. 8 is a bottom view of the invention illustrated in FIG. 1;

FIG. 9 is a right, front perspective of a speaker showing the first embodiment of the new design in a second configuration;

FIG. 10 is a left, rear perspective view of the invention illustrated in FIG. 9;

FIG. 11 is a front view of the invention illustrated in FIG. 9; FIG. 12 is a rear view of the invention illustrated in FIG. 9; FIG. 13 is a right side view of the invention illustrated in FIG. 9;

FIG. 14 is a left side view of the invention illustrated in FIG. 9;

FIG. 15 is a top view of the invention illustrated in FIG. 9; FIG. 16 is a bottom view of the invention illustrated in FIG. 9;

FIG. 17 is a right, front perspective view of a speaker showing a second embodiment of the new design;

FIG. 18 is a left, rear perspective view of the invention illustrated in FIG. 17;

FIG. 19 is a front view of the invention illustrated in FIG. 17; FIG. 20 is a rear view of the invention illustrated in FIG. 17; FIG. 21 is a right side view of the invention illustrated in FIG. 17;

FIG. 22 is a left side view of the invention illustrated in FIG. 17;

(Continued)

FIG. 23 is a top view of the invention illustrated in FIG. 17; and,

FIG. 24 is a bottom view of the invention illustrated in FIG. 17.

The broken lines in the drawings depict portions of the speaker that form no part of the claimed design.
